UNITED STATES PATENT OFFICE.

GEORGE N. PIFER, OF CLEVELAND, OHIO.

COATING-MACHINE.

No. 877,120.

Specification of Letters Patent.

Patented Jan. 21, 1908.

Application filed August 9, 1906, Serial No. 329,899. Renewed May 27, 1907. Serial No. 375,959.

To all whom it may concern:

Be it known that I, GEORGE N. PIFER, a citizen of the United States, residing in Cleveland, Ohio, have invented certain Improvements in Coating-Machines, of which the following is a specification:

The object of my invention is to provide for the effective application to one side of a strip or sheet of paper or other material 10 (hereinafter, for convenience, simply referred to as a "sheet") of a coating of any material which is of a fluid nature, or is susceptible of being rendered fluid and maintained in a fluid condition during the coating operation.

15 My invention, while of general application, has been designed especially for coating photographic paper or film with sensitized emulsions, particularly those which contain a large percentage of pigment.

20 In the accompanying drawing Figure 1 is a longitudinal section of a coating machine constructed in accordance with my invention and Fig. 2 is a plan view of the same, omitting certain heating devices shown in Fig. 1.

25 1 represents a frame having bearings in which are mounted shafts 2 and 3, provided, respectively, with drums 4 and 5, the shaft 3 also having a pulley 6, which is driven, by means of a belt 7, from a pulley 8 on another 30 shaft 9 mounted in bearings on the frame. A shaft 10 is mounted so as to be vertically adjustable between the shafts 2 and 3, and on this shaft are disks 11 and 12, preferably flanged, as shown in Fig. 2.

35 The sheet *x* of paper or other material which is to be coated, passes first over the drum 4, thence under the flanged disks 11 and 12, and thence over the drum 5, consequently that portion of the sheet of paper 40 which is in contact at the ends with the disks 11 and 12 forms a trough extending from one disk to the other, and in this trough is deposited the material of which the coating is to be formed, this material being of a permanently

45 fluid character, or one which can be rendered and maintained fluid by the application of heat.

The level of the fluid in the trough is maintained at a point below that at which the 50 strip *x* comes into contact with the disks 11 and 12, and said strip *x*, during its passage

through the machine, is maintained in sufficiently close contact with said disks to prevent any leakage from the ends of the trough. As an aid to the maintenance of such close contact I may employ endless belts 13, one for each disk, these belts passing around the drums 4 and 5, beneath the strip *x*, and also passing with the latter beneath the disks 11 and 12, tension being imparted to the belts in any appropriate manner, as for instance by means of a suspended weight 14 having a pulley 15 engaging the lower run of each belt.

When the material of which the coating is to be formed is one which requires to be heated in order to maintain it in a fluid condition, such heat may be applied directly to the material, as by means of a steam or hot water box 16 dipping into the same, or the heat may be applied through the paper *x*, or other material to be coated; as by means of an external heating box 17 supplied with hot water or other fluid into which the sheet *x* dips. In practice either of these methods of heating the coating material may be employed to the exclusion of the other, and where it is not desired to impart a definite downward pressure to the disks the weight of the latter and their shaft 10 may be relied upon to maintain them in contact with the 50 said sheet as it passes beneath them, this being especially the case if said shaft 10 is provided with other disks or drum sections 19, between the disks 11 and 12, for the purpose of dividing the trough into sections in order 55 to apply the coating material to the sheet *x* in the form of strips, as shown in Fig. 2.

It will be noted that the sheet of paper, in connection with the disks 11 and 12, forms what is practically a trough with a constantly 90 moving bottom, consequently the coating material deposited in said trough is maintained in a continuous state of agitation and the paper or other material constituting the sheet *x* will be coated with the best and richest portion of said material which naturally sinks to the bottom of the trough, especially if such material is an emulsion containing a large percentage of pigment. It will be noted also that the ascending side of the 100 trough is the delivery side, and, in consequence, the coating is formed by the material

carried up by this side of the trough in its ascent, the thickness of the coating being dependent upon the degree of fluidity of the coating material and the speed of movement 5 of the strip to be coated, and being independent of any gage bars or scrapers.

My improved coating machine is therefore preferable for many purposes to that type of machine in which the material to be 10 coated is passed beneath a roller dipping into a body of coating material, not only because of the automatic agitation of the material which results from the construction which I have adopted, but also because 15 the coated sheet of paper or other material leaves the machine with the coated side uppermost, instead of undermost as usual, a result of this difference being that the coated sheet can be passed at once over heating drums or other available heating surfaces, which may be in contact with the sheet throughout its entire width.

Where one or more intermediate disks or drum sections 19 are employed the same may, 25 if desired, be hollow and heated by means of steam or other fluid, in order to maintain the coating material in the trough in a fluid condition.

While I prefer the use of rotating disks as 30 a means of guiding the sheet α so that the latter will form a trough for the reception of the coating material, fixed guides may, if desired, be employed for the purpose, and fixed guides may also be used in place of the 35 rotating drums 4 and 5. Owing to the fact that the coating is never in contact with any foreign body it presents a smooth and uniform appearance free from lines or streaks, as is necessary in a sensitized coating for 40 photographic purposes.

I claim:—

1. A coating machine having a tank for holding the fluid mass of coating material, the sheet to be coated forming an ascending 45 delivery side of said tank in contact with said fluid material.

2. A coating machine having supports for the sheet to be coated, and means for directing the sheet between the said supports to 50 form a tank with movable bottom and ascending delivery side in contact with the fluid mass of coating material.

3. A coating machine having guides for so directing the sheet to be coated as to form a 55 trough with closed ends and ascending side for the reception of the fluid mass of coating material.

4. A coating machine having guides for so directing the sheet to be coated as to form a 60 trough with closed ends, descending side, movable bottom, and ascending side in contact with the fluid mass of coating material contained in the trough.

5. A coating machine having guides for so

directing the sheet to be coated that the 65 same forms a trough for the reception of the coating material, and means for pressing said sheet into contact with said guides.

6. A coating machine having guides for so directing the sheet to be coated that the 70 same forms a trough for the reception of the coating material, and endless belts pressing said sheet into contact with said guides.

7. A coating machine having guides for so directing the sheet to be coated that the 75 same forms a trough for the reception of the coating material, said guides comprising end and intermediate members whereby the trough is divided into sections.

8. A coating machine having guides for so 80 directing the sheet to be coated that the same forms a trough with ascending side for the reception of the fluid mass of coating material, and means for applying heat to said material to maintain it in a fluid condition. 85

9. A coating machine having guides for so directing the sheet to be coated that the same forms a trough with ascending side for the reception of the fluid mass of coating material, and means for maintaining said material in a fluid condition by heat applied 90 through the sheet which is being coated.

10. A coating machine having a pair of rotating drums, and interposed guides whereby the sheet to be coated is so directed in its passage from one drum to the other as to form a trough with ascending side for the reception of the fluid mass of coating material. 95

11. A coating machine having a pair of rotatable disks constituting guides whereby the sheet to be coated is so directed as to form a trough with ascending side for the reception of the fluid mass of coating material. 100

12. A coating machine comprising a pair of rotatable drums and an interposed pair of 105 rotatable disks constituting guides whereby the sheet to be coated is so directed as to form a trough with ascending side for the reception of the fluid mass of coating material.

13. A coating machine having a pair of rotatable drums, an interposed pair of rotatable disks constituting guides whereby the sheet to be coated is so directed as to form a trough for the reception of the coating material, and endless belts passing around said 110 drums and contacting with the sheet to be coated, where the same is in contact with the guiding disks.

14. A coating machine having a pair of rotatable drums, an interposed pair of rotatable disks constituting guides whereby the sheet to be coated is so directed as to form a trough for the reception of the coating material, endless belts passing around said drums and contacting with the sheet to be coated 115 where the same is in contact with the guiding disks, and means for imparting tension to said belts. 120

15. A coating machine having a rotatable shaft with end and intermediate disks thereon constituting guides whereby the sheet to be coated is so directed as to form a trough 5 with ascending side for the fluid mass of coating material, the intermediate disk or disks dividing said trough into sections.

In testimony whereof, I have signed my name to this specification, in the presence of two subscribing witnesses.
